UNITED STATES PATENT OFFICE

99,049

DESIGN FOR A SHOE OR SIMILAR ARTICLE

Henry B. Rosenthal, Boston, Mass.

Application November 20, 1935, Serial No. 59,665

Term of patent 3½ years

To all whom it may concern:

Be it known that I, Henry B. Rosenthal, a citizen of the United States, residing in Boston, in the county of Suffolk, in the State of Massachusetts, have invented a new, original, and ornamental Design for a Shoe or Similar Article, of which the following is a specification, reference being had to the accompanying drawing, forming part thereof.

Figure 1 is a plan view of a shoe, showing my new design.

Figure 2 is a side perspective view of the shoe.

The dominant feature of the present design resides in the ornamental effect obtained by a

shoe vamp having closed sides and open instep, a T-strap extending longitudinally of said opening, and a plurality of straps extending from one edge of the sole to the opposite edge thereof, all straps crossing the instep opening, one of said straps coming out of the sole adjacent the heel, some of said straps coming out of the arch, and the remaining straps coming out of the sole intermediate the arch and toe, as shown.

I claim:

The ornamental design for a shoe or similar article, substantially as shown and described.

HENRY B. ROSENTHAL.
